[57] **CLAIM**

The ornamental design for a battery container and display package, as shown and described.

DESCRIPTION

FIG. 1 is a perspective view of a battery container and display package showing our new design;
 FIG. 2 is a left side elevational view thereof; the right side elevational view being a mirror image thereof;
 FIG. 3 is a front elevational view thereof;
 FIG. 4 is a rear elevational view thereof;
 FIG. 5 is a top plan view thereof; and,
 FIG. 6 is a bottom plan view thereof.
 The broken line showing of batteries is for illustrative purpose only and forms no part of the claim.
